UNITED STATES PATENT OFFICE.

FRANCIS R. DRAVO, OF PITTSBURGH, PENNSYLVANIA, ASSIGNOR TO DRAVO CONTRACTING COMPANY, OF PITTSBURGH, PENNSYLVANIA, A CORPORATION OF PENNSYLVANIA.

PADDLE-WHEEL-BOAT DRIVE.

Application filed May 7, 1927. Serial No. 189,568.

This invention relates to paddle wheel boat drives, and particularly to drives for boats employing a plurality of paddle wheels.

In operating paddle wheel boats, it is often 5 undesirable to operate all of the paddle wheels. When running down stream it may be desirable to use only a single wheel. When internal combustion engines are employed it is particularly desirable to throw a wheel out 10 of operation. A steam engine may be operated over a relatively wide speed range but this is not true of Diesel engines employed for boat drives. When maneuvering the boat, as for example when approaching a 15 lock or a wharf, low speeds can be much more readily attained by cutting a wheel out of operation entirely than by attempting to operate with the engines at reduced speed.

When a paddle wheel is put out of operation it is undesirable to let it drag. It should 20 be free to rotate idly as otherwise it offers considerable resistance and also interferes with steering.

I provide a boat drive having a plurality 25 of paddle wheels with separate drive means for the same and means for disengaging a paddle wheel from its drive means so as to permit idling of the disconnected paddle wheel. With this arrangement one or more 30 paddle wheels may be cut out of operation as desired and the boat operated on the remaining paddle wheel, or wheels. Since the disconnected wheels are free to idle, they do not act as a drag, nor do they interfere with 35 steering. The arrangement is also of advantage when starting the engines.

I preferably employ two paddle wheels at 40 the stern of the boat and place the prime movers forwardly of the wheels. The prime movers are connected to the wheels through gearing and clutches are employed adjacent the prime movers. The gearing is made reversible so that the drive shaft of the disconnected wheel may turn freely while the boat 45 is running.

The drawing is a top plan view partly broken away showing the present preferred form of my invention as applied to a stern wheel paddle boat.

50 The drawing shows a boat having a hull indicated generally by the reference character 2. A paddle supporting frame 3 is formed at the rear end of the boat and pad-

dle wheels 4 and 5 are mounted therein. The 55 rudders are indicated at 6.

Each paddle wheel is provided with a spur gear 7 meshing with a pinion 8. The pinion 8 is mounted on an intermediate shaft 9 and is connected through bevel gearing 10 to a drive shaft 11 extending longitudinally of 60 the boat. The gear connection is more specifically described and claimed in the copending application of Bernard H. Kersting, Serial No. 148,222, filed November 13, 1926.

Each drive shaft 11 is connected to an internal combustion engine 12 through a clutch 13 having an operating handle 14. The shaft 11 is provided with flexible couplings 15 to take care of twisting or warping of 65 the boat frame and paddle supporting frame 70 under load.

If it is desired to use full power, both engines are operatively connected to their respective paddle wheels 4 and 5 through the 75 clutches 13. There are many occasions, as for example, when running down stream or when approaching a lock or a wharf, when it is desired to cut one of the paddle wheels out of operation. It would not be satisfactory to merely run one engine and leave the other 80 engine stationary without in some way disconnecting the paddle wheel from the idle engine. Unless the idle paddle wheel is disconnected, it will offer considerable resistance 85 to movement of the boat and will also interfere with steering. With my construction the shaft 11 may be disconnected by its prime mover simply by operating the clutch lever 14. The paddle wheel then is free to rotate 90 as the gear connection to the shaft 11 is operable in either direction; in other words, the gear is "reversible" as opposed to "irreversible" drives such as some worm gearing.

My construction is very simple and the 95 paddle wheels are readily controlled. The use of longitudinally extending shafts with the prime mover placed forwardly of the paddle wheels is desirable, since it makes the clutch levers more readily accessible. The employment of a plurality of paddle wheels 100 at the rear of the boat is particularly desirable because the tendency of the boat to travel to one side with only one paddle wheel operating is materially less than where side paddle wheels are employed.

I have illustrated and described a pre-

ferred embodiment of my invention and a modification thereof, but it will be understood that the invention is not limited to the form shown as it may be otherwise embodied within the scope of the following claim.

I claim:

A boat drive comprising a pair of paddle wheels having shafts extending crosswise of the boat, a separate drive means for each

paddle wheel, each drive means being connected to its paddle wheel through gearing engaging the outer end of the paddle wheel shaft, and means for disengaging a paddle wheel from its drive means so as to permit idling of the disconnected paddle wheel. 10

In testimony whereof I have hereunto set my hand. 15

FRANCIS R. DRAVO.
